UNITED STATES PATENT OFFICE.

FRANK RICHARDSON STAFFORD, OF PHILADELPHIA, PENNSYLVANIA.

DIE.

1,314,611.

Specification of Letters Patent.

Patented Sept. 2, 1919.

Application filed August 22, 1916. Serial No. 116,346.

To all whom it may concern:

Be it known that I, FRANK RICHARDSON STAFFORD, a citizen of the United States of America, residing at Philadelphia, in the 5 county of Philadelphia and State of Pennsylvania, have invented certain new and useful Improvements in Dies, of which the following is a specification, reference being had therein to the accompanying drawing.

10 My invention relates to dies. It has for its object the attainment of certain improvements in dies as a product and as tools. The objects may be briefly stated as follows: (1) The formation of the working dies as separate 15 units interchangeably mounted on a body to be held in a press or otherwise; (2) the production of such unit dies by means of master dies, with mathematical precision so that they are not only perfectly 20 interchangeable, but also capable of duplication individually; (3) the holding of the said dies in working position on the body or bodies automatically with perfect precision; (4) the construction and arrangement of 25 both master dies and the working dies so as to insure long life and lack of strain in use. Ancillary features of the invention and improvement will sufficiently appear from the detailed statement hereinafter.

30 My invention is illustrated in the accompanying drawings in which—

Figure 1 is a plan view showing a set of three unit dies mounted in working position on a body or holder.

35 Fig. 2 is a longitudinal section of Fig. 1 on the line 2—2 thereof.

Fig. 3 is a plan view of a master die for forming the unit dies of Figs. 1 and 2. It also represents the hub punch or duplicate 40 of the master for the same purpose.

Fig. 4 is a section on the line 4—4 of Fig. 3.

Fig. 5 is a plan view showing a trimming die and holder for trimming the outside 45 of the article.

Fig. 6 is a cross section on the line 6—6 of Fig. 5.

Figs. 7, 8 and 9 are sectional views showing three stages in the formation of the 50 trimming die of Figs. 5 and 6.

Fig. 10 is a perspective view of the article to be produced by the tools of the preceding figures.

Referring to Figs. 1 and 2, 1 indicates the 55 body for the working dies, which has its upper surface 2, and may have its other

surfaces, machined, hardened and ground perfectly true. Resting upon the surface 2 are the unit dies 3, 4 and 5, each of which has a broad base and beveled sides, and has 60 its base and top preferably ground both before and after hardening, and its beveled sides made perfectly true, in a manner to be presented explained. Each of these dies has in its top or crown a sunken impression of 65 one half or side of the article shown in Fig. 5. The impression in die 3, by which the first operation is performed, is somewhat rounded so as to cause the metal being worked to flow properly into form. The 70 die 4 has the impression sharp for fully forming the article, without trimming the flash from the outside edges, except such as are of considerable thickness or mass, as for example the ends of the part marked 6 in 75 Fig. 10. The die 5 has the same sharp impression as the die 4, but outside of this impression the metal of the die is cut away or shaped so as to produce sharp edges, as indicated at 7 in Fig. 2, for the purpose of 80 trimming off superfluous metal from the article, so far as possible.

It will be understood that the article shown in Fig. 10 is selected for purposes of illustration only, and that the shape and 85 proportions of each die may be varied according to its uses, without departing from the invention. The specific form of article and the specific form and arrangement of the set of tools illustrated and described 90 herein, are for drop forging, on hot metal, the particular metal in this case being iron or steel; but certain operations which will be pointed out, are performed when the metal is cold; and by making slight changes 95 which will be apparent to those skilled in the art, these tools are perfectly applicable to cold stamping, as required in the manufacture of such articles as jewelry, and many others.

100 Each of the dies in Figs. 1 and 2 is drilled to receive a dowel pin 8, and all the dies are held in position on the body 1 by a clamping plate 9 which for convenience is also drilled to receive dowel pins 10, and is 105 secured to the body by bolts 11. The clamping plate has an opening fitting over each die, of the same shape in plan as the body of the die, and accurately beveled to fit closely against the beveled sides of the die, 110 and to hold the latter firmly against the body surface 2 when the bolts 11 are set up.

The complete set of tools comprises a pair of assemblages, each member of the pair being identical with the single assemblage shown in Figs. 1 and 2, except that they are necessarily complements of each other. That is to say the impressions in the dies are "rights and lefts." One member of the pair is secured to the bed plate of the press (not shown) as by means of the dove tail 12, and the other member is secured to the drop head. The method of securing these members forms no part of the present invention, and may be varied according to circumstances.

In order to make each die interchangeable, that is to say to make perfect duplicates, and also to simplify and render more efficient their manufacture, I produce the dies 3, 4 and 5, or any equivalent form of working unit dies by means of master dies illustrated as to one appropriate type in Figs. 3 and 4. In these figures, 13 indicates a heavy collar of steel, having a central opening through it, with opposite flared or beveled entrances 14 and 15, and an intermediate straight sided portion 16. The flared openings 14 and 15 are of the precise shape and dimensions of the unit dies 3, 4 and 5, and the central opening 16 has the same lateral dimensions and shape as the top or crown of each die. In the opening 16 is fitted with a driving fit, a hub of a master tool 17, which also includes a part 19, the parts 17 and 19 being secured together by the pin 18. This assemblage constitutes the master tool. One part of this tool part 19 (see Fig. 3) has the same contour as the article of Fig. 10, in plan. This part 19 is made from a bar of steel planed to shape and is then driven into a corresponding opening in the collar 13 and secured by the pin 18. The upper and lower faces, 20 and 21, of the part 19, are formed to reproduce the opposite halves of the shape of the article.

As will hereafter appear, the working dies 3 and 3^a of a pair such as shown in Fig. 4 are formed by forcing them toward each other into the beveled entrances 14 and 15, by which their faces receive sunken impressions from the projections 20 and 21, and their sides are simultaneously formed with a perfect and accurate bevel.

The operation is as follows:

Having the article, or a sample thereof, or drawings, the first step is to make the collar 13 and the master punch including the hub 17. The latter is made preferably in two parts *i. e.* the punch 19 and the hub 17, as shown in Figs. 3 and 4 and heretofore described. A pair of blanks 3 and 3^a, which have been first shaped, which may be done by drop forging them hot, and removing the scale, are inserted in the entrances 14 and 15, and the assemblage shown in Fig. 4 is

then placed in a hydraulic press and subjected to very heavy pressure. By this means, the blanks 3 and 3^a receive in their faces impressions from the opposite punch faces 20 and 21 and also have sides precisely beveled by the beveled sides 14-15 of the collar. When properly ground and hardened, these two parts 3 and 3^a may then be filed away as perfect master dies.

In the further practice of my invention, the punch including the hub 17 is removed and a solid metal blank (not shown) put in its place. The master dies 3 and 3^a are then placed in position, and the assemblage is again subjected to heavy pressure in the hydraulic press. The result is the formation from the solid blank of a solid hub punch constituting a perfect replica of the two-part master punch including the hub 17. This solid metal blank punch is then hardened and left in the collar 13 for use in producing the working dies 3, 4 or 5. By repeated operations as many of these working dies may then be produced as desired, the blanks 3 and 3^a typifying the cold metal blanks which are struck up into perfect dies, both as to their impressions and their contours, ready for use as shown in Figs. 1 and 2.

It is to be noted that the method of clamping the trimming die in place shown in Figs. 5 and 6 is essentially the same as that illustrated in Figs. 1 and 2. I consider myself the original and first inventor of this construction of clamping and centering and shall claim the same and the apparatus therefor broadly hereinafter.

It should also be noted that a characteristic feature of this invention lies in the simultaneous pressing of opposite blanks against the opposite working faces of a master punch, as shown in Fig. 4, whereby the holder and other parts are relieved of strain and perfect impressions are produced.

The manner of use of the working dies 3, 4 and 5, and their complements, is as follows:

The assemblage having been secured in the drop press, a hot bar is inserted between the first pair of dies 3, and the drop head lowered. The resulting blow initially forms the article, and as the drop head rises this is removed by means of the gate projection connecting it to the bar, and placed between the second pair of dies 4. Here the finished shape is imparted to the article by a second blow, but it is not trimmed and the gate projection is left upon it. The openings for this gate projection are indicated at 37 in Fig. 1. After the second blow, the article is again removed, and for a third operation is placed between the pair of dies 5. The succeeding blow then completes the surface finish of the article and trims the bulk of metal away from the outer and inner sur-

faces, leaving nothing but a very thin film in places, and if the dies are new, leaving practically nothing at all. The perfection of this trimming, and the slightness of the 5 flash left thereafter, depends almost entirely upon the skill of the mechanic who sets up the tools in the press.

Many other modifications and modes of application of this invention might be detailed but it is thought the foregoing will be sufficient to enable skilled engineers and mechanics to fully receive the benefits flowing from the novel features presented. The principal two of these novel features, are, 10 first, the manufacturing of the working dies as interchangeable units, and their mounting upon a body by bringing together perfect hardened surfaces, self-centering and self-adjusting, and second, the manufacture 15 of these dies by means of master dies and punches, and particularly the feature of the hub punch making two opposite impressions at one stroke, and with the surrounding collar perfectly and precisely shaping and finishing 20 two complementary dies to form a pair. To those who are familiar with the processes of tool making heretofore practised, it will be at once apparent that with this invention I effect not only vastly better 25 results, making glass finished dies and punches with mathematical precision, and within any degree of accuracy detectable by micrometric measurements; but also effect great economy in the cost of dies. Instead 30 of having to cut and mill and grind, and hand-tool the metal out from the contours or edges of the punch and die, I save all this fine work, with its tedious consumption 35 of time, and at one blow produce a more 40 perfect die or pair of dies, than an expert tool maker could get out in a week.

Having thus described my invention what I claim and desire to secure by Letters Patent is:—

45 1. A tool of the class described comprising a body, interchangeable unit dies resting upon said body, and clamping means having an accurately fitted beveled projection surrounding and resting against each die, with 50 means to secure said clamping means to the body.

2. A tool of the class described comprising a body, a die having a base accurately fitted to the surface of the body and having beveled sides, and a clamping plate having a 55 beveled opening surrounding and accurately fitted to the beveled sides of the die, with means for securing said clamping plate to the body.

3. A forming tool comprising the following instrumentalities: a body of considerable mass provided with means to secure it, meditately or immediately, in a press, and having its working face smooth and true, a die head of relatively small mass having its 60 base accurately ground to fit solidly against the working face of the body, means secured in the body of the die to center the latter in fixed position, and a clamping plate secured upon the body, with an opening to take 65 the die, the walls of said opening being inclined symmetrically with respect to the center, and engaging similarly inclined and accurately registering walls of the die, whereby accuracy, solidity as a unit, and 70 permanency of adjustment, as between the die head and its body, and quick and easy 75 interchangeability of the working parts of the die are secured.

4. A forming tool, comprising a body 80 portion, a plurality of dies adapted to be arranged upon the body portion and tapering outwardly away from the body portion, a clamping plate provided with a corresponding number of openings which taper 85 outwardly away from the body portion and are adapted to snugly receive the dies, and means to secure the clamping plate to the body portion.

5. A forming tool, comprising a body portion, a plurality of dies adapted to be arranged upon the body portion and tapering outwardly away from the body portion, a clamping plate provided with a corresponding number of openings which taper 90 outwardly away from the body portion and are adapted to snugly receive the dies, separate 95 guide means for the clamping plate carried by the body portion, and means to lock the clamping plate to the body portion. 100

In testimony whereof I affix my signature.
FRANK RICHARDSON STAFFORD.
